CLOCK DISPLAY DEVICE

Fford Burchell, New York, N. Y., assignor to Burchell-Holloway Corporation, New York, N. Y., a corporation of New York

Application November 5, 1946, Serial No. 707,957

4 Claims. (Cl. 40—130)

1

This invention relates to display devices embodying the use of polarized light and birefringent material or vectographs and, more particularly, it relates to a display device of this character involving a clock in such a way that its works are used simultaneously for operating the clock hands and for operating necessary movable parts of the display device so that the hands move about a clock face having embodied therewith designs of changing colors or of changing forms or both visible thereon.

An object of this invention is to provide devices of this character that are not only useful but highly ornamental and pleasing to the eye.

Another object of this invention is to provide devices of this character that are simple in construction, easy to assemble and which may be manufactured at comparatively low cost.

Still another object of the invention is to provide display devices of the character described that are particularly useful for advertising display purposes and which embody the use of a clock face and changeable designs associated with the face, whose changes are effected by the use of the clock works or motor that operate the hands of the clock.

Another object of the invention is to provide devices of this character that may be constructed without extensive modification of existing clocks.

To the accomplishment of the foregoing and such other objects as may hereinafter appear, the invention comprises the novel construction and arrangement of parts hereinafter to be described and then sought to be defined in the appended claims, reference being had to the accompanying drawing forming a part hereof, which shows merely for the purposes of illustrative disclosure, some embodiments of the invention, it being expressly understood, however, that changes may be made in practice within the scope of the claims without digressing from the inventive idea.

In the drawing in which similar reference characters denote corresponding parts:

Fig. 1 is a front elevational view of a device embodying the invention;

Fig. 2 is a vertical section taken along line 2—2 of Fig. 1 and viewed in the direction of the arrows;

Fig. 3 is an enlarged fragmentary sectional view taken along line 3—3 of Fig. 1 and viewed in the direction of the arrows; and

Fig. 4 is a diagrammatic illustration of the principles of operation embodied in the practice of the invention.

Referring to the drawing 10 denotes a casing

2

having an open front face defined by a flange 11 and a rear wall 12. An electric clock works or motor 13, for example, of the "Telechron" type or any other conventional type of electric clock works or motor is secured suitably as by the screws 14 to the casing wall 12. This clock motor 13 has on its shaft 13a the drive gears G₁, G₂, G₃ arranged to mesh respectively with gears G₄, G₅, G₆ and thereby to drive the usual concentrically arranged hollow shafts 15, 16 and a third or inner shaft 17 which extend forwardly of the motor 13 through an opening 18 in the wall 12. The minute and hour hands 19 and 20 are mounted on the respective hollow shafts 15 and 16 timed for rotation in conventional manner at the forward ends of these respective shafts. The latter and also the forward end of shaft 17 extend forwardly of the open face 11 of the casing 10 and through an opening in a covering sheet 21 or member 21. This sheet 21 preferably is of light transmitting translucent or transparent isotropic material such as glass, matte cellulose acetate or "Vinylite" or of other isotropic translucent or transparent material. The front face of this sheet 21 serves as a clock dial and is provided with the usual clock face markings such as the numerals and, if desired, minute markings (not shown) and the like.

One or more electric lights 22 are carried in conventional sockets 23 which in turn are supported within the casing 10 behind the covering sheet 21. The electric power to operate these lights may be provided through a conventional electric circuit (not shown), provided, if desired, with a switch (not shown) for operation from the same electric power source that is utilized to drive the motor 13.

The conventional sweep-second hand of the ordinary electric clock which usually would be mounted upon the innermost shaft 17 for rotation with it is replaced by a composite disc or arm 24. Likewise this shaft 17 is geared to run at a faster rate than the single revolution per minute of the usual sweep-second shaft. It is geared to make, for example, six revolutions per minute instead of one revolution per minute. The disc or arm 24 comprises a sheet or length of light polarizing material 25 such as "Polaroid" mounted upon a co-extensive sheet 26 of isotropic, transparent or translucent supporting material made, for example, of the same material as that of sheet 21.

A glass crystal or transparent cover 27 of other suitable material is provided to cover the clock dial and hands and to enclose the disc or arm 24.

This cover 27 is dish shaped and secured together with the sheet 21 to the annular flange 11 at the front face of the casing 10, for example, by the clamping ring 28.

A second sheet 29 of polarizing material similar to that of sheet 25 is carried within the transparent cover 27 in front of the rotatable sheet 25. This sheet 29 functions as an analyzer. Suitably secured or cemented to the stationary polarizing sheet or analyzer 29 is a coextensive isotropic sheet 30 of material similar to the sheet 21. This sheet 30 which is adapted to lie between the two polarizing sheets 25 and 29 has applied to it a design D. This design may, for example, be a mosaic-like construction built up of birefringent elements 40, 41, etc. Such elements, for example, consist of "Scotch cellulose tape" or other birefringent sheet material arranged in single or in superposed layers. The design D embodying these elements may, for example, be constructed of birefringent material in any of the manners described in Burchell and Ivins Patent No. 2,393,968, granted February 5, 1946.

The design D shown includes also so-called vectograph pictures 42, 43 also mounted on sheet 30. The vectographs conventionally are superposed photographic images visible respectively in lights having different angles of polarization. In the alternative, the design D may consist either of birefringent elements or of vectographs. If combined, the procedure, for example, taught in my copending application, Serial No. 661,522, filed April 12, 1946, now Patent No. 2,483,314, issued September 27, 1949, may be used in the construction of the design. Therefore, wherever in this specification a design D is referred to, it is to be understood to refer to one consisting either of birefringent elements alone, or of vectographs alone or of combinations of birefringent elements and of vectographs. In other words, the design is to be considered as containing elements exhibiting changeable characteristics to the observer when viewed in polarized light of varying polarity.

The structure consisting of the sheet 30 bearing the design D assembled with the polarizing sheet 29 as by cementing with isotropic cementitious material such as matte cellulose acetate, "Vinylite," or the like ordinarily has a different coefficient expansion from that of the transparent cover 27. In order, therefore, to mount it effectively and permanently to the cover 27 without danger of detachment because of the different rates of expansion, a frame-like member 45 is provided. This frame-like member 45 is preferably of paper, fiber or plastic composition or of other flexible or yieldable material. The frame-like member 45 has one or more perimetrical corrugations 46 provided in its surface and laterally, oppositely extending peripheral flanges 47, 48. The outermost flange 47 is cemented securely to the inner face of the crystal 27 with glue, cement or other adherent of any effective type. The assembled sheets 29, 30 are dimensioned to overlie the inner flange 48 and the adjacent faces of the sheet 29 and the flange 48 are joined together with glue, cement or any other adherent of effective type. Since the flange 48 is not secured to the crystal 27, any temperature changes resulting either in the expansion or contraction of the sheets 29, 30 and cover 27 at different rates produce stresses or strains which are taken up in the corrugation 46. Hence, any tendencies for separation of the sheets 29, 30 or of the cover 27 from the frame member 45 are eliminated. Thus,

the sheets 29, 30 are held securely in place on the cover 27 and in front of the rotating polarizing sheet 25. If desired, the design D may be built up on the inner face of sheet 29 and the sheet 30 may then be eliminated.

When the clock motor 13 is operated as by being plugged in the conventional electric circuit and the lights 22 are on, the composite disc 24 rotates with the shaft 17 and simultaneously, the minute and hour hands 19, 20 move over the dial face of the disc 21 to denote time. The light transmitted from the light source or sources 22 passes through the translucent sheet 21, the polarizing sheet 25, the sheets 29, 30, the design D, and forwardly through the cover 27. An observer E positioned in front of the cover 27 viewing the transmitted light will see unique changes taking place in the design D. For example, if the design D is built up of birefringent elements only, the continual change in angle of polarization of the light transmitted by the rotating disc 24 will effect a series of color transformations in the design D visible to the observer E. On the other hand, if the design D is made up of vectographs 42, 43 only, one of the vectograph pictures 42 will disappear or merge into the second of the vectograph pictures 43 and vice versa during the rotation of disc 24. Furthermore, if a combination of birefringent material and vectographs is used, a combination of the two effects just described will be seen by the observer, that is, color changes will occur while the vectograph pictures change or merge one into the other.

The design D may be changed at any time by removal of the cover 27 and the positioning of a substitute design in place of the original one.

Other clock works having three shafts may be substituted for the clock works 13. Likewise for more slowly changing effects, the disc 24 could be mounted on one of the other shafts 15 or 16 in addition to the hands 19 or 20 or the shaft 17 could be geared to run more slowly.

The entire construction described results in a novel clock and color display device, is pleasing in appearance, has great advertising value and may be constructed without extensive modification of existing structures.

While a specific embodiment of the invention has been shown, it is to be understood that changes may be made in practice and are contemplated. There is no intention, therefore, of limitation to the exact details shown and described.

What is claimed is:

1. In a device of the character described, a dish-like casing having an open front, a light transmitting isotropic covering for the open front, a light source supported in said casing, a clock works having a driven shaft extending through said casing and said covering, a polarizing disc mounted on said shaft for rotation therewith, minutes and hour hand shafts similarly extending through said casing and covering, minute and hour hands mounted on the respective of said two last-named shafts, a polarizing member positioned in front of said polarizing disc, a design responsive to changes in polarity of light interposed between said disc and said polarizing member, a transparent covering for the front face of said device, and expandable means secured to said polarizing member and to said transparent covering for positioning said polarizing member in front of said polarizing disc.

2. In a device of the character described, a casing having an open front, a light transmitting

translucent covering for said front, a light source supported in said casing behind said covering, a clock works having a driven shaft extending through said covering, a light polarizing disc mounted on said shaft for rotation therewith in front of said covering, a transparent covering positioned in front of the polarizing disc and secured to said casing, a light polarizing member, a frame-like member having a perimetrical corrugation and perimetrical flanges one secured respectively to said polarizing member and the other secured to said transparent covering to mount said polarizing member in front of said polarizing disc and a design positioned to lie between said polarizing disc and said polarizing member, said design being composed of elements exhibiting changeable characteristics when viewed in polarized light of varying polarity created by the rotation of said polarizing disc with said shaft.

3. In a device of the character described, a casing having an open front, a light transmitting covering for said front, a light source supported in said casing behind said covering, a clock works having a driven shaft extending outwardly of said covering, a light polarizing member secured to said shaft for rotation therewith in front of said covering, a transparent covering positioned in front of said light polarizing member and spaced therefrom, a second light polarizing member, an expandable frame secured to said second light polarizing member and to said transparent covering to mount said second polarizing member in front of said first-named polarizing member, and a design positioned to lie between said two light polarizing members, said design being composed of elements exhibiting changeable characteristics when viewed through the second polarizing member in polarized light of varying polarity created by the rotation of said first-named polarizing member with the shaft on which it is secured.

rotation of said first-named polarizing member with said shaft.

4. In a device of the character described, a casing having an open front, a light transmitting covering for said front, a light source supported in said casing behind said covering, a clock works having concentric shafts extending outwardly of said covering, a light polarizing member secured to one of said shafts for rotation therewith in front of said covering, time denoting hands secured to others of said shafts, a transparent covering positioned in front of said light polarizing member and spaced therefrom, a second light polarizing member, an expandable frame secured to said second light polarizing member and to said transparent covering to mount said second polarizing member in front of said first-named polarizing member, and a design positioned to lie between said two light polarizing members, said design being composed of elements exhibiting changeable characteristics when viewed through the second polarizing member in polarized light of varying polarity created by the rotation of said first-named polarizing member with the shaft on which it is secured.
